UNITED STATES PATENT OFFICE.

JOHN B. BOLTON, OF LAWRENCE, MASSACHUSETTS, ASSIGNOR TO UNIVERSAL
WINDING COMPANY, OF PORTLAND, MAINE, A CORPORATION OF MAINE.

WINDING-MACHINE.

1,087,433.

Specification of Letters Patent. Patented Feb. 17, 1914.

Application filed November 12, 1912. Serial No. 730,966.

To all whom it may concern:

Be it known that I, JOHN B. BOLTON, a citizen of the United States, residing at Lawrence, in the county of Essex and State 5 of Massachusetts, have invented certain new and useful Improvements in Winding-Machines, of which the following is a specification.

My invention relates to improvements in 10 winding machines for winding thread or yarn into filling cops or bobbins such as are employed in the shuttles of looms.

My improvement consists particularly in 15 providing in the machine a "bunch-builder" or device for winding a preliminary section of yarn on the bobbin with a relatively short traverse before the main portion of the bobbin is wound with the maximum traverse; the "bunch" being designed to coöperate 20 with the "feeler-devices" which control the filling-replenishing mechanism of the loom to cause the insertion of a fresh bobbin in the shuttle when the one in place runs out. The bunch-building device is designed to 25 automatically control the reciprocating mechanism for the thread-guide, at the beginning of the winding, to cause the guide to lay the thread with a short traverse throughout several courses or layers and to 30 then act to increase the extent of traverse of the guide to its normal length.

The invention is fully described in the following specification, illustrated by the accompanying drawings, in which—

35 Figure 1 is a longitudinal elevation of a winding machine of well-known construction, showing my bunch-building device applied thereto, the frame of the machine being illustrated in section to reveal the mechanism contained therein; Fig. 2, a plan view of the same; Figs. 3, 4 and 5, enlarged detail views of the controlling device for the traverse-mechanism, illustrating the parts in progressive stages of their operation; 45 Fig. 6, a plan view of the same; Fig. 7, a detail view of the ratchet-cam-wheel which operates the device.

My invention is shown as applied to a machine of the same general type as that 50 described in U. S. Patents Nos. 940,489 and 946,881, granted Nov. 16, 1909, and Jan. 18, 1910, respectively, to S. W. Wardwell.

The basic machine consists essentially of a rotating winding-spindle B and a reciprocating traverse-bar C, the latter arranged

opposite the spindle, and adapted to carry the thread-guide G, which, besides its movement with the bar, is fed progressively outward thereon to build the cop in superimposed conical layers. The winding-spindle 60 B is mounted in a bearing *a* in the main frame A of the machine and is rotated from the main driving-shaft E by means of skew-gears *e*, *e'*. The traverse-bar C slides in a quill-shaped bearing *a'*, which has an extension *a*² extending through a bore in the side of the frame A, and is reciprocated from a rocker-arm F mounted on the continuously-oscillated shaft D. My traverse-controlling device operates directly in connection with 65 the arm F and is arranged to automatically adjust the point of connection of the traverse-bar C with the arm to vary the operative length of the latter and regulate the length of traverse of the thread-guide as 70 more fully explained hereinafter.

The traverse-bar C is preferably constructed in two parts C' and C², the main portion C' sliding in the bearing *a'*, as before explained, and the extension C² connected thereto at its outer end by a pin-and-slot coupling *c*. The opposite end of the extension C² is mounted in a bushing *c'* which is swiveled in an outboard bearing *j* supported on a bracket J extending from 80 the frame A. The coupling *c* allows the inner end of the extension C² to swing inward from the plane of the axis of the main portion C' of the bar, as shown in Fig. 2, while the outer end of the bar swings in 85 the swiveled bushing *c'*. This arrangement is the same as that described in U. S. Patent 940,489, above referred to, and provides that the contact means carried on the traverse-bar, and arranged to feed the thread-guide 90 along the winding-spindle, shall contact with the first layers of yarn wound on the bobbin *a* before the base of the cop is built up to its maximum diameter. The progression or contact-mechanism is arranged as 95 now briefly described, a more comprehensive description being given in the patent just referred to.

The thread-guide G is preferably supported on a thread-guide holder or arm *g*, 105 of bifurcated form, having two legs *g'*, *g'* terminating in bearings *g*², *g*² surrounding the bar C². Between the bearings *g*², *g*² is an internally threaded sleeve or nut *h* which carries a relatively thin disk H called the 110

contact-wheel. The bar C^2 is formed with screw-threads c^2 extending approximately half way around its circumference and a spring h' is secured to the guide-holder g 5 with its end bearing on a flange h^2 of the nut h . The spring h' acts to normally press the nut h into position to engage its threads with the threads c^2 on the bar C^2 , but the bore of the nut is of sufficient diameter to 10 allow its threads to pass over those on the bar when the nut is pressed in the opposite direction against the force of the spring. It will be seen that while the machine is operating the nut h is engaged with the threads 15 on the bar C^2 so that the turning of the wheel H will feed the thread-guide along the winding-spindle, but by releasing the nut from engagement with the threads on the bar the guide can be slid back to adjust 20 it in position to begin the winding of a new bobbin.

Mounted on the end of the bar C' is a "former" K , so termed because it acts to direct the movement of the contact-wheel H 25 away from the winding-spindle during the building of the base or heel of the bobbin and therefore determines the form of the latter. The former K has an arm k arranged with its edge k' at an angle to the 30 axis of the winding-spindle and by adjusting the arm at different angles the taper of the base of the bobbin can be regulated. Adapted to bear on the edge k' of the arm k is a follower-arm g^3 extending rearwardly 35 from the thread-guide holder g . Sliding in a bore at the inner end of the bar C^2 is a spring-pressed plunger c^3 , adapted to bear against the inclined face c^4 of the coupling-plate c and tending to normally hold the 40 bar C^2 in position to align its axis with that of the bar C' . The swinging movement of the bar C^2 is limited by its pin c^5 sliding in the slot c^6 of the plate c and with the follower g^3 bearing on the inner end of the 45 former-arm k the end of the bar is held with the pin at the inner end of the slot as shown in Fig. 2. This provides that the contact-wheel H will be maintained in close proximity to the surface of the wooden bobbin or cop-tube x at the beginning of the winding so that its periphery will contact 50 with the first layers of yarn wound on the latter at the rearward end of each stroke of the thread-guide. The contact of the 55 wheel with the surface of the yarn, during the rotation of the winding-spindle, acts to turn the wheel to feed the thread-guide outward along the spindle in the manner now well known to those versed in the art. As 60 the thread-guide feeds outward along the traverse-bar C^2 the follower-arm g^3 slides along the incline of the arm k and allows the contact-wheel to recede from the axis of 65 the winding-spindle in accordance with the growth in diameter of the winding. As the

follower g^3 reaches the end of the arm k the base of the bobbin or cop attains its maximum diameter and the bar C^2 assumes a position in alignment with the bar C' . Henceforth, the two sections C' and C^2 of 70 the traverse-bar C are reciprocated in the same plane, as one continuous bar, and the contact-wheel H engages the bobbin at the rearward end of each reciprocation at a point on the base of its forward conical end. 75 In this way the bobbin grows by longitudinal extension, the conical layers forming a substantially cylindrical body terminating in the tapered delivery end or nose.

Referring now to Figs. 1, 3 and 4, the arm F which acts to reciprocate the traverse-bar C is connected thereto by a link L pivoted at l' on the bar. The opposite end of the link carries a pin or stud l adapted to slide in a curved slot f formed in the arm F . By sliding the stud l up and down in the slot f the operative length of the arm can be varied to vary the extent of reciprocation imparted to the traverse-bar C and, through the latter, to the thread-guide G . 90 At the beginning of the winding of a bobbin the stud l is held at the lower end of the slot f and will therefore move through an arc of relatively short radius when the arm F is oscillated, so that the thread-guide is reciprocated with a comparatively short traverse to build the "bunch" on the bobbin. When a sufficient number of layers of winding have been deposited to complete the bunch; or, more properly speaking, when the required length of yarn has been wound into the bunch, the stud l is shifted to the upper end of the slot f and the traverse-bar C will then be reciprocated with the maximum length of movement to cause the thread-guide to traverse the yarn to the full or normal extent required to wind the main portion of the bobbin. The means for automatically shifting the stud l along the slot f 100 consists essentially of a scythe-shaped lever N with devices for operating the lever as now described: The lever N is pivoted on a screw n screwed into the side of the bearing a' which latter is secured in the side of the frame A , as previously explained. Preferably, the lever N is formed of sheet-metal with a downwardly-extending curved arm n' terminating in a forked extension n^2 bent back at right-angles and formed with a slot n^3 , see Fig. 6, adapted to receive the link L . 110 The lever N has an ear n^4 adjacent its pivot point to which is attached one end of a spring M , secured at its opposite end to the side of the frame A by means of a hook m . The spring M tends to normally hold the lever N in its lowermost position with the stud l at the bottom of the slot f . The lever N is also formed with a downwardly-projecting, pointed extension n^5 adapted to be engaged by an abutment o on the inside of 120 125 130

the cam-wheel O through which the lever is operated. The cam-wheel O, formed with a hub o' , is pivoted on a stud o^2 projecting from the side of the bearing o' and its periphery is provided with ratchet-teeth o^3 . The abutment o is formed on or attached to its inner face, as before described, and has a straight edge o^4 extending outward from the hub o' and rounding into the curved edge 5 o^5 which follows the periphery of the wheel through a distance of four teeth. These faces coöperate with the pointed extension n^5 on the lever N as hereinafter more fully explained. On the outer face of the wheel 10 O is another abutment o^6 which also has a curved edge o^7 following the periphery of the wheel through a distance of approximately four teeth, the two abutments being arranged substantially ninety degrees apart 15 or at a distance of about one-quarter of the circumference of the wheel.

Referring to Figs. 5 and 6, an arm P, pivoted on the bearing stud o^2 of the wheel O, extends downwardly therefrom and carries a pawl p at its lower extremity formed with a hooked end p' adapted to engage the teeth o^8 on the periphery of the wheel O. A screw o^9 screwed into the end of the stud o^2 serves to maintain the wheel O and arm P 20 in place on the stud. The pawl p is pivoted on a stud p^2 and a wire spring q fastened at q' to the arm P is arranged with its end bearing on the back of the pawl to maintain the latter in engagement with the teeth on 25 the wheel O. Extending through an inclined hole a^3 in the side of the frame A, see Figs. 5 and 6, is a rod R having its end swiveled on a stud p^3 projecting from the arm P, and secured in place on the stud by 30 the cotter-pin p^4 . Secured to the outer end of the rod R by a pin s' is a finger-piece S terminating in the flat push-button s . A coiled spring T surrounds the rod R between the side of the frame A and the inner end of the finger-piece S, and tends to 35 force the rod outward from the frame. A pin r , driven down through the rod R, engages the inner side of the frame to limit the movement of the rod under the action 40 of its spring T. Its movement in the opposite direction is limited by a sleeve s^2 on the rod R, the end of which is adapted to come into contact with the outer side of the frame A. By pushing the rod R inward against 45 the action of the spring T the arm P can be rocked on its pivot and the pawl p moved thereby to turn the wheel O in the direction indicated by the arrow 2, Fig. 5. This manually-operated means for turning the wheel 50 O is provided in order that the device may be set at the beginning of the winding, as more fully explained hereinafter. The pawl p also serves a second purpose of preventing the backward turning of the wheel O, 55 that is, in an opposite direction to that indi-

cated by the arrow 2, since the rearward movement of the arm P is limited by the pin r in the rod R. The automatic turning of the wheel O is effected by a pawl U pivoted on a stud u at the end of a rocker-arm V. 70 The end of the pawl U is maintained in engagement with the teeth o^8 by a spring u' coiled about the stud u , see Fig. 6. The arm V is secured to a shaft W by means of a pin w and the shaft has a continuous oscillating 75 motion during the operation of the machine. Preferably, the shaft W is connected to be rocked from the means which oscillate the rock-shaft D, not here shown, so that the arms F and V move in unison, although this 80 is not essential providing the two arms are operated synchronously.

The operation of the whole machine is as follows: Referring to Figs. 1 and 2, a usual form of cop-holder, such as the wooden bobbin x here shown, is placed on the winding-spindle B and after the thread-guide G has been adjusted in position the yarn is drawn through it and its end secured to the bobbin. It is then necessary to set the traverse-controlling device to begin the winding with the short traverse to form the bunch on the bobbin. During the winding of the main portion of the bobbin, and at the stopping of the machine upon its completion, 90 the parts of the traverse-controlling mechanism are in the position illustrated in Fig. 5. It will be noted that as here shown the stud l of the link L is at the upper end of the slot f in the arm F and the lever N is in its raised position with the point n^5 resting on the abutment o of the wheel O. To set the device the finger-piece S is pressed by the operator to push the rod R in the direction indicated by the arrow 3, Fig. 5. This movement of the rod R swings the arm P on its pivot and acts through the pawl p to turn the wheel O in the direction indicated by the arrow 2. One push on the rod R is sufficient to turn the wheel O forward through 100 a distance of several teeth and when the rod is released the spring T returns it to its normal position with the pin r abutting the side of the frame A. With the rod in this position the arm P acts through the pawl p to prevent backward turning of the wheel O, as previously explained. The turning of the wheel O forward carries the abutment o out from under the point n^5 of the lever N and the spring M then acts to draw the lever downward into the position illustrated in Fig. 3. The link L being engaged by the forked extension n^2 of the lever N, is thus carried downward by the movement of the latter and the stud l is moved to the lower 110 end of the slot f in the arm F. The machine is now ready to wind the bunch on the bobbin and its operation is started by throwing the clutch-devices into engagement, the parts 115 of this mechanism being here shown but not 120 125 130

described since their operation is well known to those versed in the art. As the machine starts to operate the arm F is rocked back and forth by the shaft D and the traverse-bar C is reciprocated with a relatively short extent of traverse while the stud l is being held at the bottom of the slot f. During the oscillation of the arm F the arm V is also rocked from the shaft W which is preferably connected to the same cam or other similar means, as previously described. The rocking of the arm V acts through the pawl U to turn the wheel O forward one or more teeth at each oscillation as may be desired. If a comparatively large amount of yarn is to be wound into the bobbin the movement of the arm V is regulated to advance the wheel a single tooth at a time, but if a lesser amount is desired the movement of the arm can be increased to advance the wheel several teeth at each oscillation, it being understood that the turning of the wheel regulates the time of action of the traverse-shifting mechanism as later explained. The intermittent turning of the wheel O carries the abutment o around its axis until, near the completion of one rotation of the wheel, the edge o⁴ of the abutment comes into contact with the edge n⁶ of the extension n⁵ of the lever N. Now, as the rotation of the wheel O continues the extension n⁵ will ride outward on this edge o⁴, as illustrated in Fig. 4, until finally its extremity is carried up onto the edge o⁵. During this action, while the lever N is being raised by the abutment o bearing on its extension n⁵ the end of the lever N acts to raise the link L until the stud l is carried to the extreme upper end of the slot f in the lever F. The raising of the lever N is accomplished during the last few forward advances of the wheel O and while the link L is being moved upward the traverse-bar C will be reciprocated with a gradually-increasing extent of traverse until finally the maximum extent is attained. That is to say, the change from the minimum to the maximum traverse does not occur instantly but is progressive, there being several reciprocations of the thread-guide with a gradually increasing extent of traverse. Referring now to Fig. 5, as the edge o⁵ of the abutment o comes under the point of the extension n⁵, the edge o⁷ of the abutment o⁶ on the front of the wheel O is brought under the end of the pawl U, it being understood that this end of the pawl is broad enough to lap over the teeth o⁸, or, in other words, to overhang the wheel O on its outer edge. This action raises the pawl O so that its end clears the teeth o⁸, as shown in Fig. 5, and hence the continued oscillation of the arm V will cease to have any effect on the wheel O. That is to say, after the wheel O has been turned to this position the end of the pawl U will simply ride on

the edge o⁷ of the abutment o⁶ and therefore no further rotation of the wheel takes place. This provides that the abutment o shall remain under the point of the extension n⁵ of the lever N so that the latter will be maintained in its raised position with the stud l at the upper end of the slot f during the rest of the winding. With the stud l held at the upper end of the arm F the maximum extent of traverse is imparted to the traverse-bar C so that the remainder or body portion of the bobbin is wound with full length layers. At the completion of the bobbin the device is set again, as before described, to cause the traverse mechanism to reciprocate the thread-guide with the minimum extent of traverse to begin the bobbin with the short layers which form the bunch.

In the drawings I have shown the cam-wheel O constructed with forty-four teeth and if the pawl U is arranged to advance the wheel one tooth at each oscillation then it will require forty-four oscillations to turn the wheel through one complete rotation. Now, as the arm F oscillates in synchrony with the arm V there would be forty-four reciprocations of the thread-guide during one rotation of the wheel O. As a matter of fact, however, it does not require quite a complete rotation to bring the abutment o under the extension n⁵ of the lever N and, furthermore, the wheel O is advanced several teeth in setting the device. That is to say, when the rod R is operated its movement will turn the wheel O through a distance of several teeth, this provision being made to insure that the wheel is moved far enough to release the lever N from the abutment o. It will therefore be seen that if the device is set to advance the wheel O one tooth at each oscillation of the thread-guide something less than forty-four layers or courses will be wound before the maximum traverse is attained. This is a liberal provision and for most purposes a much less amount of yarn is required in the bunch. In practice, I have found that from eighteen to twenty reciprocations of the guide will give a sufficient length of yarn in the bunch and therefore the pawl U is preferably regulated to advance the wheel O two teeth for each oscillation of the traverse-arm F.

Various modifications might be made in the form and structure of the parts of my device without departing from the spirit or scope of the invention.

Therefore, without limiting myself to the exact arrangement shown and described, what I claim is:

1. In a winding machine, the combination with the winding-spindle and thread-guide, of an oscillating arm for reciprocating the guide, means adapted to connect the guide with the arm at different distances

from the axis of the latter, a member for controlling the position of the connecting-means on the arm, and means to operate said member to retain the connecting-means

5 adjacent the axis of the arm during a predetermined number of reciprocations of the guide to wind with a relatively short traverse and to cause it to positively shift the connecting-means away from the axis of 10 the arm to adapt the guide to lay the yarn with a longer traverse.

2. In a winding machine, the combination with the winding-spindle and thread-guide, of an oscillating arm for reciprocating the guide, means adapted to connect the guide with the arm at different points along the latter to vary its operative effect on the guide, a lever for adjusting the connecting-means along the arm, and automatic 20 means to operate the lever to positively shift the connecting-means immediately from one end of the arm to the other after a predetermined number of reciprocations of the thread-guide.

25 3. In a winding machine, the combination with the winding-spindle and thread-guide, of an oscillating arm for reciprocating the guide, means to connect the guide at different points along the arm to vary 30 the operative effect of the latter, a lever engaging said connecting-means, a spring to maintain the lever in position to hold the connecting-means adjacent the axis of the arm, and automatically-operated means to 35 move the lever to positively shift the connecting-means to the end of the arm after a predetermined number of reciprocations of the thread-guide.

4. In a winding machine, the combination 40 with the winding-spindle and thread-guide, of an oscillating arm for reciprocating the guide, means connecting the guide with the arm and adapted to be shifted along the latter to vary the operative effect 45 of its throw, a lever engaging said connecting-means, and a cam to operate said lever to positively shift the connecting-means from a point adjacent the axis of the arm to the end of the arm after a predetermined 50 number of reciprocations of the thread-guide.

5. In a winding machine, the combination 55 with the winding-spindle and thread-guide, of an oscillating arm for reciprocating the guide, a link connecting the guide with the arm, means to adapt the link to slide on the arm to vary the operative effect of the latter, a lever engaging the link, a cam to operate the lever to positively shift 60 the link to the end of the arm, and means to operate the cam during a predetermined number of reciprocations of the thread-guide.

6. In a winding machine, the combination 65 with the winding-spindle and thread-guide,

of an oscillating arm for reciprocating the guide, a link connecting the guide with the arm and arranged to be shifted along the latter, a lever engaging the link to shift it along the arm, a cam for moving the lever, 70 said cam formed with ratchet teeth, a pawl to turn the cam, and means to operate the pawl.

7. In a winding machine, the combination with the winding-spindle and thread-guide, 75 of an oscillating arm for reciprocating the guide, a link connecting the guide with the arm and adapted to be shifted along the latter, a lever engaging the link, a ratchet-cam-wheel for operating the lever to positively 80 move the link to the end of the arm, a continuously-operated pawl for turning the cam-wheel, and means to render the pawl inoperative with respect to the cam-wheel after the link has been shifted to the end of 85 the arm.

8. In a winding machine, the combination with the winding-spindle and thread-guide, 90 of an oscillating arm for reciprocating the guide, a link connecting the guide with the arm and adapted to be shifted along the latter, a lever engaging the link, a ratchet-cam-wheel for operating the lever to positively 95 shift the link to the end of the arm, a pawl for turning said wheel, and means on the wheel to engage said pawl to render the latter inoperative after the link has been shifted to the end of the arm.

9. In a winding machine, the combination with the winding-spindle and thread-guide, 100 of an oscillating arm for reciprocating the guide, a link connecting the guide with the arm and adapted to be shifted along the latter, a lever engaging the link, a ratchet-cam-wheel, a pawl to turn said wheel, an abutment on the wheel adapted to engage the lever to raise the latter, and a second abutment on the wheel adapted to engage the pawl to raise it from the ratchet teeth after 105 the link-operating lever has been raised.

10. In a winding machine, the combination with the winding-spindle and thread-guide, 110 of an oscillating arm for reciprocating the guide, a link connecting the guide with the arm and adapted to be shifted along the latter, a lever for shifting the link formed with an inclined face, a ratchet-cam-wheel, a pawl to turn the wheel, a continuously-oscillated arm for operating the pawl, an abutment on the cam-wheel adapted to 115 engage the inclined face on the lever to raise the latter, and a second abutment on the wheel adapted to raise the pawl from the ratchet teeth after the lever has been raised.

11. In a winding machine, the combination with the winding-spindle and thread-guide, 120 of an oscillating arm for reciprocating the guide, means to connect the guide with the arm at different points along the latter to vary the operative effect of its 125

throw, a lever for adjusting the connecting-means along the arm, automatically-operated means to move the lever to positively shift the connecting-means away from the axis of the arm at a predetermined point in the winding, and manually-operated means to return the lever to its initial position with the connecting-means adjacent the axis of the arm after the completion of the winding.

10 12. In a winding machine, the combination with the winding-spindle and thread-guide, of an oscillating arm for reciprocating the guide, a link connecting the guide with the arm and adapted to be shifted along the latter, a lever engaging the link, means to operate the lever to positively shift the link to the end of the arm at a predetermined point in the winding, and manually-operated devices to adjust the lever-operating means to cause the return of the link to its initial position after the completion of the winding.

13. In a winding machine, the combination with the winding-spindle and thread-guide, of an oscillating arm for reciprocating the guide, a link connecting the guide with the arm and adapted to be shifted along the latter to vary the effect of its throw, a lever engaging said link, a spring 30 engaging the lever to normally hold it with the link at a point adjacent the axis of the arm, automatically-actuated means to operate the lever to shift the link away from the axis of the arm at a predetermined point in the winding, and manually-operated means to release the lever-operating means to cause the link to be returned to its initial position by the action of the spring.

14. In a winding machine, the combination with the winding-spindle and thread-guide, of an oscillating arm formed with a longitudinal slot, a link connected to the guide and carrying a stud slideable in the slot in the arm, a lever arranged with its end 45 engaging the link, automatically-actuated means to operate the lever to slide the stud to the outer end of the slot in the arm, a spring acting to normally retain the stud at the opposite end of the slot, and means 50 to release the lever-operating means to allow the spring to return the lever to its initial position.

15. In a winding machine, the combination with the winding-spindle and thread-guide, of an oscillating arm for reciprocating the guide, a link connecting the guide with the arm and adapted to be shifted along the latter, a lever connected to the

link, a ratchet-cam-wheel for operating the lever to positively shift the link to the end 60 of the arm, a pawl for turning said wheel, automatic means to actuate the pawl, a second pawl adapted to prevent backward turning of the wheel, and manually-operated means to actuate the second pawl to 65 turn the wheel and adjust the lever to its initial position after the completion of the winding.

16. In a winding machine, the combination with the winding-spindle and thread-guide, of an oscillating arm for reciprocating the guide, a link connecting the guide with the arm and shiftable along the latter, a lever to shift the link, a ratchet-wheel to move the lever, automatically-operated 70 means to rotate the wheel, a pawl to prevent backward rotation of the wheel, and a push-rod to actuate the pawl to turn the wheel and adjust the lever to its initial position after the completion of the winding. 80

17. In a winding machine, the combination with the winding-spindle and thread-guide, of an oscillating arm for reciprocating the guide, a link connecting the guide with the arm and shiftable thereon, a lever 85 to shift the link, a ratchet-wheel to move the lever, automatically-operated means to rotate the wheel, an arm pivoted on the axis of the wheel, a pawl on said arm adapted to engage the teeth on the wheel, a push-rod connected to the arm to swing the pawl 90 to rotate the wheel manually, a spring to return the rod to its initial position, and means to limit the movement of the rod under the action of the spring to hold the 95 pawl in position to restrain the wheel from backward rotation.

18. In a winding machine, the combination with the winding-spindle and thread-guide, of an oscillating arm, a link connecting the guide with the arm, a lever engaging the link and formed with an inclined face, a ratchet-wheel, an abutment on said wheel, automatically-operated means to turn the wheel to engage the abutment with 100 the inclined face of the lever to move the latter and shift the link, and manually-operated means to turn the wheel to release the abutment from engagement with the lever.

In testimony whereof I affix my signature 110 in presence of two witnesses.

JOHN B. BOLTON.
